UNITED STATES PATENT OFFICE.

GEORGE ZINT, OF WAPAKONETA, OHIO.

CONTACT-MOUNTING MEANS.

Original application filed March 26, 1923, Serial No. 627,773. Divided and this application filed January 2, 1924. Serial No. 683,975.

To all whom it may concern:

Be it known that I, GEORGE ZINT, a citizen of the United States, residing at Wapakoneta, in the county of Auglaize and State of Ohio, have invented certain new and useful Improvements in Contact-Mounting Means; and I do declare the following to be a full, clear, and exact description of the invention, such as will enable others skilled in the art to which it appertains to make and use the same.

My invention relates to improvements in mounting means for electrical contacts and the present disclosure is directed more particularly to an electrical switch for railway signalling, said switch including a pair of co-operable contacts and binding posts in connection therewith, the object of the invention being to provide an effective connection between said contacts and binding posts, which in addition to establishing the necessary electrical conductivity, will prevent turning of the contacts and binding posts.

The construction of the switch is protected in my pending U. S. application, Serial No. 627,773, filed March 26, 1923 and the subject matter of the present application forms a division of said application.

In the accompanying drawing which forms a part of this application,

Figure 1 is an elevation showing the application of the invention to a switch of the type set forth.

Figure 2 is a sectional view showing more particularly the contact mounting means.

Figures 3 and 4 are perspective views of the two insulators and associated parts, used in mounting the contacts.

Briefly mentioned, the switch disclosed, includes a casing C adapted to be mounted at one side of a railway rail R, a wheel-operated, spring-returned arm A and a pair of contacts 25 and 26 controlled by the movement of said arm.

For mounting the contacts 25 and 26 and insulating them from each other as well as

from the casing C, I have provided a novel construction. The numeral 27 designates 50 an inner insulator contacting with one end of the casing C, said insulator having an inwardly extending boss 28 passing through an opening in the casing and formed with openings passing through said boss, through 55 which openings, the stationary ends 29 of the contacts extend, said ends being preferably of circular section. The extremities of the contacts 29 are bent laterally upon the outer face of the insulator 27 as 60 indicated at 30 and are received frictionally in grooves 31 formed in the heads of binding posts 32. These binding posts pass through openings in an outer insulator 33 and are out of alinement with the openings 65 through which the contact ends 29 pass. The inner surface of the insulator 33 is preferably grooved as indicated at 34 to receive the terminals 30. Screws or the like are passed through openings 35 in the 70 outer and inner insulators 33 and 27 respectively, and are threaded or otherwise connected with the casing C, so as to hold the two insulators against opposite sides of the contact extremities 30 as well as to 75 hold said insulators securely upon the casing. When attaching the necessary wiring to the binding posts 32, it is of course necessary to first loosen and then tighten the nuts of said binding posts, but attention is 80 directed to the fact that these posts are held against rotation by their engagement with the contact extremities 30. Similarly, the contacts 25 and 26 cannot rotate on account of having their lateral extremities received 85 in the grooves 31 of the binding posts.

By providing the construction shown and described or a substantial equivalent thereof, simple and inexpensive, yet efficient means are provided for effectively mounting 90 the binding posts and contacts and securing electrical contact between them. As excellent results are obtained from these details, they are preferably followed, but within the scope of the invention as claimed, 95 numerous minor changes may be made.

I claim:

1. In a contact mounting means, a pair of insulators secured together and having openings out of alignment with each other, a contact passing through the opening of one insulator and having a lateral end clamped between the two insulators, and a binding post in the opening of the other

insulator having a grooved head whose groove receives said lateral contact end. 10

2. A structure as specified in claim 1; one of said insulators being grooved to receive a portion of said lateral contact end.

In testimony whereof I have hereunto affixed my signature.

GEORGE ZINT.
